DAVID PATON, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,893, dated June 4, 1872.

Specification describing a new and original Design for a Carpet, invented by DAVID PATON, of Halifax, in the county of York, England.

The accompanying photograph fully illustrates my invention.

This invention relates to a new design for carpets or other fabrics; and consists in the arrangement of a bouquet of flowers in a pointed shield of peculiar form, and in the new ornamental scroll-work which surrounds the shield. The latter has four small rosettes

formed on the inner edge of its outline, as shown, and a scalloped inner border. The bouquet branches out at the ends through the shield, the branches constituting the basis for the outer scrolls.

I claim as my invention—

DAVID PATON.
